PATTY FORMING MACHINE

Walter F. Shelgren, Bradford, Pa.

Application June 8, 1933, Serial No. 674,952

7 Claims. (Cl. 107—8)

This invention relates to an improved patty-forming machine of the character shown in my co-pending application for a similar invention filed January 21, 1933, Serial Number 652,916.

Generally stated, the invention seeks to refine the machine so as not only to produce a more feasible commercial article but also to provide a more practical and convenient device.

More especially, the invention seeks to provide an improved follower in conjunction with the meat hopper of the device and wherein the follower may be easily and quickly removed bodily from the hopper so that the hopper may be readily loaded.

And the invention seeks, as a still further object, to provide a follower wherein the follower spring employed may be readily tensioned for forcing the meat downwardly within the hopper and wherein retrograde slippage of the tensioning means for said spring will be effectually obviated so that the follower will effectually function at all times to exert a downward pressure on the meat within the hopper.

With the foregoing and other objects in view, the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification, Figure 1 is a front elevation of my improved machine.

Fig. 2 is a vertical sectional view on the line 2—2 of Fig. 1.

Fig. 3 is a transverse section on the line 3—3 of Fig. 1.

Fig. 4 is an enlarged detail elevation particularly showing the anchoring head for the tensioning barrel of the follower spring.

Fig. 5 is a detail section on the line 5—5 of Fig. 4.

Fig. 6 is a detail section on the line 6—6 of Fig. 5.

Fig. 7 is a detail perspective showing one of the pawls of the anchoring head, and

Fig. 8 is a detail section showing a slightly modified form of anchoring head.

In carrying the invention into effect, I employ a flat substantially semi-circular lobate base 10 having a depending marginal flange 11 and projecting from the base, flush with the upper face thereof, are equi-distantly spaced lateral ears

12. Adjacent these ears, the base is provided

at its lower side with preferably circular sockets 13 in which are fixed pads 14 of rubber or the like so that when the base is placed on a table, as conventionally illustrated at 15, the pads will prevent marring or scratching of the table. At a point midway of the concave portion of the front edge of the base, the flange 11 thereof is thickened to provide a boss 16 and depending from the front lobes of the base are L-shaped brackets 17 adapted to abut the adjacent edge of the table 10 for positioning the base with respect thereto so that the midpoint of the concave edge of the base lies flush with said edge of the table. Screwed through the brackets are clamp screws 18 adjustable for securely binding the base to the table and preferably, these screws are provided with caps 19 of rubber or the like to afford a secure frictional grip on the table.

As particularly seen in Fig. 2, the boss 16 of the base 10 is recessed to receive a fixed upstanding stud 20 and mounted to oscillate upon said stud is a substantially semi-circular forming knife 21 lying flat upon the base. As best seen in Fig. 3, this forming knife is provided with spaced patty-forming openings 22 and projecting from the forward edge of the knife, midway between said openings, is an operating lever 23 carrying an upstanding handle 24. The openings 22 may be of any approved size and these openings are preferably tapered toward their upper ends so that meat patties formed in said openings may be readily discharged downwardly from the openings.

Resting flat on the forming knife 21 is a top plate 25 of the same shape as the base and provided with ears 26 overlying the ears 12 of the base. Extending freely through the ears 26 but screwed into the ears 12 are clamping screws 27 and interposed between the winged heads of said screws and the ears of the top plate are equalizing springs 28. Thus the screws 27 may be adjusted for clamping the forming knife 21 between the top plate and the base while the springs 28 will function to equalize the tension on the ears 26 and prevent accidental fracture of the top plate.

Centrally, the top plate 25 is, as particularly seen in Fig. 2, provided with a discharge opening 29 surrounding which is an upstanding collar 30 spaced radially from said opening to provide a ledge or stop shoulder 31 at the lower end of the collar and, as will be observed, the collar is undercut at said shoulder to provide an annular cavity 32. Fitting snugly in the collar is an upstanding cylindrical hopper 33 which may be

formed of suitable sheet metal and, as will be observed, the lower margin of the hopper is spun outwardly to provide a flange 34 engaging in the cavity 32 for rigidly and securely connecting the 5 hopper with the top plate. At its upper end, the hopper 33 is flared to provide an overhanging annular flange 35, and formed in said flange, as particularly seen in Fig. 5, are circumferentially spaced notches 36.

10. Detachably mounted upon the upper end of the hopper is an anchoring head including a sectional sleeve 37 from the ends of the sections of which project mating flanges 38. Arranged near the upper ends of the flanges 38 are bolts 39 pivotally connecting the sections of the sleeve with each other, these bolts being reversely presented and each extending freely through one flange of each sleeve and being threaded into the confronting flange of the other sleeve so that 15 each of the sections carries one of the bolts. Washers 40 are provided on the bolts 39 for spacing the sleeve sections apart. Arranged near the lower ends of the flanges 38 are similarly mounted bolts 41 oppositely presented with respect to the bolts 39 and disposed on the bolts 25 41 are springs 42 each acting on one of the sections of the sleeve 37, respectively, for normally holding the lower ends of said sections at the limit of their movement toward each other. 30 In thus mounting the springs, the tension thereof is equally distributed between the sleeve sections. Projecting from each of the sections of the sleeve 37 is a pair of diverging legs 43 which are provided at their lower ends with depending 35 hooks 44 adapted to freely pass through the notches 36 of the flange 35 of the hopper 33 so that after the head has been lowered to dispose the hooks through said notches, the head may be rotated to the position shown in Fig. 5 for 40 engaging the hooks beneath the flange 35. As will be perceived, this construction also admits of ready detaching of the head. As shown in Fig. 6, each of the sections of the sleeve 37 is internally grooved near its lower end to removably 45 receive a semicircular shoe 45 and formed on the shoes, as seen in Fig. 7, are pawls 46 having beveled upper faces.

Slidable through the sleeve 37 of the anchoring head is a barrel 47 provided at opposite sides 50 thereof with longitudinally spaced pairs of openings 48 and fixed to the upper end of the barrel is a cap 49 from which extends alined lateral handles 50. As seen in Fig. 2, the cap 49 is internally recessed and the upper end of the 55 barrel 47 is spun outwardly into said recess for rigidly and securely connecting the cap to the barrel. Slidable through the cap 49 is a follower stem 51 provided at its upper end with a knob 52 for limiting the barrel 47 against upward displacement from the stem and screwed upon the lower end of the stem is a concavo-convex follower 53 snugly but slidably fitting within the hopper 33. Surrounding the stem 51 to rest at one end against the follower and at its opposite 60 end against the cap 49 of the barrel 47 is a spring 54.

In use, the anchoring head is turned on the hopper 33 until the hooks 44 of the legs 43 register with the notches 36 in the flange 35 of the hopper, when the head is lifted upwardly 70 for displacing the follower assembly as a unit from the hopper. The hopper is then, as suggested in Fig. 2, filled with meat, when the follower assembly is replaced. The handles 50 are 75 then grasped and the barrel 47 pushed down-

wardly through the sleeve 37 of the anchoring head. As shown in Fig. 6, the pawls 46 are engageable in the pairs of openings 48 but as the barrel is thus pushed downwardly, the wall of the barrel will coat with the beveled faces of said pawls for rocking the lower ends of the sections of the sleeve 37 apart so that downward movement of the barrel will be unhampered. When, however, the barrel has been shifted downwardly sufficiently to impart the desired tension to the spring 54 and a pair of openings is brought into register with the pawls 46, said pawls will be caused by the springs 42 to snap into said pair of openings so that upon release of the handles 50, the pawls will securely lock 10 the barrel against upward movement. Thus, the spring 54 will be held under tension for forcing the follower 53 downwardly and feeding the meat within the hopper 33 downwardly against the forming knife 21.

In this connection, attention is directed to the fact that when the supply of meat in the hopper 33 becomes exhausted or nearly so, the follower 53 will move into engagement with the shoulder 31 which will then serve to limit the follower 25 against further downward movement so that the follower will be held away from the forming knife 21 and by then grasping the handles 50 and pushing downwardly on the barrel 47 to free the pawls 46, the barrel may then be rotated until the openings 48 are out of line with the pawls when, of course, the barrel may be shifted upwardly and the follower assembly removed from the hopper for reloading the hopper. 30

To operate the machine, the handle 24 is 35 grasped and swung to the right, for instance, as seen in Fig. 3, to dispose one of the openings 22 in said knife beneath the discharge opening 29 of the top plate 25 when the meat in the hopper 33 will be fed downwardly by the follower 53 into 40 said opening of the knife. The knife is then swung to the left when the other opening 22 of the knife will be disposed beneath the hopper to be filled with meat while the previously filled opening of the knife will be brought into an 45 exposed position at the front of the machine so that the meat patty therein may be readily dislodged for use. Thus, each time the forming knife 21 is oscillated, a meat patty will be delivered.

The size of the meat patties delivered by the machine will, as previously stated, be determined by the circumference of the openings 22 and, as will be appreciated, the thickness of the meat 50 patties will be determined by the thickness of the forming knife 21. I have, accordingly, provided a construction wherein by simply moving the screws 27 and displacing the top plate 25, the forming knife 21 may be removed and another forming knife of either greater or less 55 thickness substituted in lieu thereof or the substituted forming knife may be of the same thickness as the forming knife 21 but may have patty-forming openings of either greater or less diameter. The size and thickness of the meat patties 60 delivered by the machine may thus be readily controlled by the choice of the putty-forming knife used and, of course, the springs 28 will provide the necessary tension on the forming knife installed regardless of the exact thickness 65 thereof.

In Fig. 8 of the drawings, I have illustrated a slight modification wherein the sections 55 of the sleeve of the anchoring head are provided with integral pawls 56 like the pawls 46, the 70 75

shoes 45, as in the prior embodiment of the invention, being eliminated. In some instances, this modified construction may be found adaptable. Otherwise, however, this variation of the 5 invention is identical with the preferred embodiment thereof and further description is accordingly believed unnecessary.

Having thus described the invention, I claim:

1. In a device of the character described, a 10 hopper, a follower movable therein, a spring for advancing the follower, a barrel accommodating said spring, the barrel being adjustably shiftable for tensioning the spring, and an articulated anchoring head carried by the hopper and mov- 15 able for locking the barrel in adjusted position.

2. In a device of the character described, a 20 hopper, a follower slidable therein and provided with a stem, a barrel accommodating said stem, a spring disposed within the barrel to act on the 25 follower for advancing the follower, the barrel being adjustably shiftable for tensioning said spring, and an anchoring head carried by the hopper and formed of pivotally connected spring- actuated sections having pawls engageable with the barrel for locking the barrel in adjusted position.

3. In a device of the character described, a 30 hopper, a follower slidable therein, a spring for advancing the follower, a barrel accommodating said spring and adjustably shiftable for tensioning said spring, a sleeve formed of pivotally connected sections having legs engaging the hopper, the sleeve slidably receiving the barrel there- 35 through, and pawls carried by said sleeve sections and engageable with the barrel for locking the barrel in adjusted position.

4. In a device of the character described, a

hopper provided at its upper end with a flange having notches therein, a follower movable in the hopper, a spring for advancing the follower, a sleeve accommodating said spring and adjustably shiftable for tensioning the spring, and an anchoring head carried by the hopper and pro- 5 vided with means engageable with said barrel for locking the barrel in adjusted position, the anchoring head having legs provided with hooks normally engaged beneath said flange for connecting the head with the hopper and movable through said notches for freeing the head, the tension of said spring operating to normally hold said hooks in contact with said flange.

5. In a device of the character described, a 15 hopper, and a follower assembly carried by the hopper and including a follower movable within the hopper, and a follower spring normally holding said assembly engaged with the hopper.

6. In a device of the character described, a 20 hopper, and a follower assembly carried by the hopper and freely detachable as a unit there- 25 from, said assembly including a follower movable within the hopper, a head to coact with the hopper for supporting the follower, and a spring for advancing the follower and normally holding the head engaged with the hopper.

7. In a device of the character described, a 30 hopper, a follower movable therein, a spring for advancing the follower, means for adjustable 35 tensioning said spring, and a head supporting said adjusting means upon the hopper and including pivotally mounted head-sections movable to engage and lock said adjusting means in adjusted position.

WALTER F. SHELGREEN. [L.S.]
